BOOT- AND SHOE-TACKING MACHINE

Karl Wollny, Weissenfels-Saale, Germany, assignor to the firm Nollesche Werke, Komm. Ges., Weissenfels, Germany

Application May 13, 1939, Serial No. 273,510
In Germany June 21, 1938

2 Claims. (Cl. 12—2)

The invention relates to nailing, tacking or pegging machines for boot and shoe manufacture.

Tacking and like machines are known wherein the gripper is closed by a closure lever controlled by a cam disc, and during the overlaying or wiping of the marginal portion of the upper is held in the closed position with reduced pressure by a step of the control cam.

According to the invention a machine of this kind is provided with two springs of different strength between the closure lever and the gripper closing device so arranged that during the upper pulling operation by means of the gripper both springs are operative and during the overlaying or wiping of the margin of the upper by the wiper only the weaker spring is operative.

The two springs may exert a closing pressure of variable strength which is adjustable individually for each spring. By this means during nailing or tacking on, especially of the toe of the shoe, a very powerful closing pressure can be obtained by the gripper and a correspondingly high tension applied to the leather for the pulling on, whereas the holding pressure, which the gripper has to exert during the overlaying operation of the leather edge, is low, and adjustable and quite independent of the gripper-closing pressure maintained during the pulling or stretching of the leather.

In stretching or pulling the upper the spring which can exert the stronger closing pressure is operative, and for the overlaying of the margin of the upper the other spring with the lower gripper-closing pressure comes into operation.

As separate adjusting devices are provided for each spring, the spring for supplying the lower holding pressure on the gripper can be completely stressed during the stretching operation of the leather so that only the strong spring is in operation whereas during the overlaying of the margin of the upper the closing pressure of the main spring on the gripper is completely released.

It is possible without further provision to equip existing machines with this supplementary arrangement, since for this purpose only the exchange of the gripper-closing lever and the control cam of the cam disc is required. This can be carried out in the simplest and quickest manner without disturbing the remainder of the machine structure. Advantageously the second spring, namely the plunger of this additional spring, is mounted in the main spring plunger carried by the gripper-closing lever, the hollow

shaft of which main plunger provides the abutment for the spring of the additional plunger.

The invention is illustrated in the accompanying drawings in my constructional arrangement by way of example.

Figure 1 shows a front view of a tacking-on machine with a known arrangement of gripper-closing lever, partly in section.

Figure 2 shows a corresponding front view of the machine with the gripper-closing lever and 10 control cam according to the invention.

Figure 3 shows a side view of the gripper-closing lever shown in Figure 2.

Figure 4 shows a view of the gripper.

Figures 5 to 7 show different working positions of the gripper-closing lever.

Figures 5a to 7a show the positions of the gripper corresponding with the lever positions shown in Figures 5 to 7.

In the known construction according to Figure 1 the gripper device 1 is brought into the closed position by the closing lever 2, whose plunger 3 bears upon the press rod 4 of the movable gripper jaw. The plunger 3 is under the influence of a spring 5 whose pressure can be regulated by a screw sleeve 6. The closing lever 2 is securely keyed on the shaft 7 on which the lever 8 is similarly rigidly connected. The roller 9 of the lever 8 lies against the closure cam 10 of the cam disc 11.

Upon the rotation of the cam 10, the spring plunger 3 is forced down on the press rod 4 by means of the roller 9 and the levers 8 and 2, so that the gripper is closed and the margin of the upper is gripped. The gripper remains closed so long as the roller 9 runs on the closure cam 10 and the jaws will be forced together with equal force during the whole of this time.

In the example of construction of the invention illustrated in Figure 2, an auxiliary plunger 12 is mounted in the spring plunger 3 and is under the influence of a spring 13.

The pressure of this spring, which can be regulated by the set screw 14 is weaker than that of the spring 5 of the main plunger 3. As a result, on the forcing down of the gripper press rod the auxiliary plunger 12 first of all yields, stressing its spring 13, and then causes a rising movement of the main plunger 3 with stressing of its spring 5.

The control cam surface 15 for the roller 9 on the cam disc 11 has a dwell step 15' which is so determined as to hold the jaws still under the pressure of the auxiliary plunger 12 and its spring 13 during the overlaying of the leather of 55

the upper. The keying of the control cam 15 on the cam disc 11 is effected through slots 16 and screws 17 so that the cam can easily be changed and adjusted. The roller 9 of the lever 8 can be maintained against the control cam 15 in known manner by means of the torsion spring 18.

In Figures 5 and 5a the commencement of the closing movement of the gripper is shown. As 10 the roller 9 runs on to the closure cam 10 the gripper-closing lever 2 is swung on to the press rod 4. In this position the gripper is still held open by its own spring 19. When on the other hand, the roller 9 has run on to the cam 15 15 (Figure 6), then first the auxiliary plunger 12, and in turn the main plunger 3, is pressed upwardly in the lever 2 so that by this time the pressure of the stronger spring 5 comes into operation on the press rod 4, and the movable jaw 20 and fixed jaw 21 of the gripper close securely on to the margin of the upper, (Figure 6a). After the stretching of the margin of the upper and during the movement of the wiper 22, the roller 9 reaches the dwell step 15' in the control cam. 25 This swings the gripper-closing lever 2 by means of the spring 18 and the springs of the plungers 3 and 12 back to some extent, so that, as shown in Figure 7, the main plunger 3 moves back to its rest position and now only the auxiliary plunger 12 with its spring 13 is operative on the 30

rod 4. The gripper is thus held closed only by a pressure corresponding to that of the spring 13 and therefore the wiper can gradually draw the edge of the upper out of the gripper. The running off of the roller 9 from the control cam 5 step 15' returns the closure lever 2 with its plungers to the rest position Figure 5.

What I claim is:

1. Boot and shoe-nailing and like machines wherein the gripper for pulling the upper is closed by a lever controlled by a lever controlled by a cam and during the overlaying of the margin of the upper is held closed but with reduced gripping power by a step of the control cam including an auxiliary plunger acting on the 15 gripper-closing device, a hollow main plunger in which the auxiliary plunger is mounted and which acts to depress the auxiliary plunger, a spring in the main plunger acting on the auxiliary plunger, and a relatively stronger spring 20 acting on the main plunger whereby during the stretching or pulling of the upper leather by the gripper both springs are operative while, on the other hand, during the overlaying of the margin of the upper only the weaker spring is operative. 25

2. A construction as defined in claim 1 wherein a set screw is mounted in the shaft of the main plunger for adjustment of the spring therein.
